(57) CLAIM

The ornamental design for a purse, as shown and described.

DESCRIPTION

FIG. 1 is a perspective view of a purse, showing my new design;

FIG. 2 is a side elevational view thereof;

FIG. 3 is a top plan view thereof;

FIG. 4 is a bottom plan view thereof;

FIG. 5 is a side elevational view thereof, opposite that shown in FIG. 2;

FIG. 6 is an end view thereof; and,

FIG. 7 is an end view thereof, opposite that shown in FIG. 6.

The broken lines shown herein are for illustrative purposes only and form no part of the claimed design.
